WATER FAUCET

Alexander Bamberger, Winnipeg, Manitoba, Canada, assignor of one-third to Joseph Ruml and one-third to Henry Kreuzer, both of Winnipeg, Manitoba, Canada

Application October 27, 1936, Serial No. 107,761
In Canada October 28, 1935

1 Claim. (Cl. 284—19)

My invention relates to improvements in water faucets and an object of the invention is to provide a device of the character herein described which automatically checks the flow of water through the faucet when dismantled for the purpose of making repairs thereto and especially when dismantled in order to replace a worn valve washer therein.

A further object of my invention is to provide 10 a device of the character herein described which eliminates the necessity of closing the main valve of the water system in a building in order to effect repairs or replacements to the faucets therein.

15 A further object of my invention is to provide a device of the character herein described which removes the necessity of supplying secondary main valves in each suite when the device is used in apartment blocks.

20 A further object of this invention is to provide a device of the character herein described which can be successfully applied to numerous types of faucets.

A further object of this invention is to provide 25 a device of the character herein described, which is simple to construct, economical to manufacture and will not easily become out of order.

With the foregoing more important objects in view and such other minor objects as may appear as the specification proceeds, my invention 30 consists essentially in the arrangement and construction of parts all as hereinafter more particularly described, reference being had to the accompanying drawing, in which:

35 Fig. 1 illustrates a cross sectional view of one embodiment of my device.

Fig. 2 shows a perspective view of the primary valve and its base as used in this embodiment of my device.

40 In the drawing like characters of reference indicate corresponding parts in the different figures.

The embodiment of my invention illustrated in Figure 1 of the drawing accompanying this 45 application consists of an outer casing 1 having a curved neck portion 2 which expands downwardly into a valve housing 3. The wall of the upper part of this housing is thickened and internally threaded as at 4 while the lower portion thereof is externally threaded as at 5.

To the housing 3, I provide a detachable nozzle 6 having a converging mouth piece 7 internally tapped to engage with the threads 5 upon the housing and having the upper periphery thereof 55 encircled by a removable collar 8 receivable with-

in a circular recess 8'. This collar is designed with an outwardly disposed handle 9 and a set screw 10 for clamping the collar in position on the nozzle. It will be evident that turning the handle will produce an inclined rotative motion 5 of the nozzle on the threaded portion 5, thereby causing an upward or downward movement thereof upon the housing 3.

Immediately superjacent the interior of the above mentioned mouth piece 7, I have furnished 10 an annular seating 11 upon which rests my primary valve 12, the upper portion thereof being recessed as at 13 to receive the usual type of faucet washer 14, the orifice through the centre of which is aligned with an elongated socket 15 15 within the valve 12 provided for a purpose later to be explained.

Below the recessed portion 13 and integral therewith, is a triangular segment 16 having the angular extremities thereof bearing against the 20 interior walls of the housing 3 to prevent lateral movement of the entire valve 12. Subjacent the triangular segment and attached thereto, I have furnished a cylindrical base 17 with a flange 18 encircling the lower periphery thereof which 25 bears upon the seating 11 in the nozzle 6. This base I have also provided with a plurality of aligned passageways 19 disposed adjacent the periphery thereof through which the water passing 30 through my faucet may flow.

Within the socket 15, a removable stem 20 is 35 inserted terminating at its upper end in an auxiliary valve 21 made integral with the stem and having an inverted conical configuration as best illustrated in Figure 1.

Engaging with the threads 4 within the housing 3, I furnish a bushing 22, the upper surface of which is provided with inwardly converging shoulders 23 to receive the conical valve 21. The lower portion of this bushing is designed with a 40 downwardly extending annular flange 24 which serves as a seating for the valve washer 14.

Having described my improved type of faucet, its mode of operation will now be explained.

During normal operation, the faucet is closed 45 by revolving the nozzle by means of the handle 9 and causing the valve washer to bear against the flange 24. To open the faucet, the nozzle is revolved to move downwardly whereupon the valve washer will withdraw from the flange and 50 allow water to flow therebetween and pass through the orifices 19 to be expelled from the mouth piece 7.

When it becomes necessary to make repairs or 55 replacements to the interior of the faucet, the

collar 8 is first loosened by withdrawing the set screw 10 whereupon the nozzle 6 may be unscrewed. During this procedure, the primary valve 12 will open while the auxiliary valve 21 5 will move downwardly and close against the bushing 22 thereby causing a cessation in the flow of water. The nozzle and primary valve may now be completely removed and after the necessary repairs have been effected, the nozzle 10 and valve thereof may be replaced, thereby again lifting the auxiliary valve and allowing the device to operate in the normal manner.

From the foregoing, it will be seen that I have devised an improved type of water faucet 15 to which repairs and replacements can be made with greater despatch than is the case with former types as by the use of this device, the necessity for closing the water main for this purpose, is eliminated.

Since various modifications can be made in the invention, and many apparently widely different embodiments of same, made within the scope of the claim without departing from the

spirit and scope thereof, it is intended that all matter contained in the accompanying specification shall be interpreted as illustrative only and not in a limiting sense and I desire only such limitations placed thereon as are specifically 5 expressed in the accompanying claim.

What I claim as my invention is:

A faucet comprising in combination with a conduit outlet externally screw-threaded upon the outer end thereof to receive a rotatable internally screw-threaded nozzle having a handle attached thereto, a primary valve and washer positioned within said nozzle to seal said outlet when said nozzle is rotated in one direction, an auxiliary reversed frusto-conical cut-off valve 15 within said outlet, a screw-threaded complementary seating for said cut-off valve, a vertical stem secured to the lower end thereof, said stem extending into a passageway formed in said primary valve, said cut-off valve proceeding downwardly under pressure or by gravity upon the removal of said nozzle.

A. BAMBERGER.
